Des. 215,118
Patented Sept. 2, 1969

215,118

LOCKING TAPE MEASURE OR SIMILAR ARTICLE

John J. Evans, Jr., Westfield, N.J., assignor to Evans-Aristocrat Industries, Inc., Elizabeth, N.J., a corporation of New Jersey

Filed June 10, 1968, Ser. No. 12,290

Term of patent 14 years

Int. Cl. D9—04

U.S. Cl. D52—1

FIG. 1

FIG. 2

FIG. 3

FIG. 4

FIG. 5

FIG. 6

FIG. 1 is a side view of the locking tape measure showing my new design;

FIG. 2 is a view of the opposite side thereof;

FIG. 3 is a top plan view thereof;

FIG. 4 is a bottom plan view thereof;

FIG. 5 is an end view as seen from the left of FIG. 1, and;

FIG. 6 is an end view as seen from the right of FIG. 1.

I claim:

The ornamental design for a locking tape measure or similar article, substantially as shown.
